ROTARY DRIER

Harlow L. Schmidt and Henry C. French, Milwaukee, Wis., assignors to The Heil Co., Milwaukee, Wis., a corporation of Wisconsin

Application July 3, 1939, Serial No. 282,592

9 Claims. (Cl. 34—57)

Our invention relates in general to improvements in the art of dehydrating bulk materials, and relates more particularly to various improvements in the construction and operation of rotary driers of the type wherein solid particles such as hay mixed with heated gases such as air, are constantly urged through a revolving drum, the dried material being separated from the heating medium at the discharge end of the assemblage.

Generally defined, an object of our invention is to provide various improvements in the construction of rotary driers, whereby the cost of construction and operation thereof is reduced to a minimum while the efficiency is enhanced to a maximum.

Some of the more important specific objects of the present invention are as follows:

To provide a drier wherein the material being treated is mixed with the drying medium and the mixture is drawn through the drying zone in a continuous stream, and in which fresh material may be introduced into the advancing stream of mixture without admitting excessive quantities of cold air to the drying zone.

To provide an improved drier assemblage wherein the dried material may be delivered direct from the zone of separation of the drying medium, or only after final cooling and removal of foreign objects such as stones or metallic particles from the final product.

To provide improved instrumentalities for protecting the various elements of a drying unit, against deterioration due to exposure to the weather and excessive heat.

To provide a self-contained complete rotary drier installation which is neat and compact in appearance, which is readily transportable and installable, and which may be operated with minimum power consumption.

To provide an improved feeder adapted to deliver uniform quantities of material to a drier drum regardless of irregularities in the primary supply, and which is safeguarded against possible damage due to overfeeding.

To provide an improved fan and power unit housing for rotary driers, which may be conveniently associated directly with the drier drum outlet and thus produces a compact installation adapted to be readily assembled.

To provide an improved automatic cooling system for the material agitating flights of a revolving drum drier or the like, whereby the life of the drum may be materially prolonged.

These and other objects and advantages of

the present invention will be apparent from the following detailed description.

A clear conception of the several features constituting the present improvement, and of the mode of constructing and of operating rotary drier installations embodying the invention, may be had by referring to the drawings accompanying and forming a part of this specification wherein like reference characters designate the same or similar parts in the various views.

10 Fig. 1 is a perspective view of a rotary drier installation embodying the invention;

Fig. 2 is an enlarged transverse vertical section through the material discharge and fan 15 housing, showing the improved product purifier in action;

Fig. 3 is a fragmentary section similar to that of Fig. 2, but showing the purifier inactive, and the parts adjusted for direct delivery of the product;

Fig. 4 is a side elevation of the delivery end of the improved drier installation, showing the parts in a position corresponding to Fig. 2;

Fig. 5 is an end view of the drier installation 25 looking toward the delivery end thereof;

Fig. 6 is a further enlarged longitudinal central vertical section through fragments of the drier drum, showing details of the air cooling system;

Fig. 7 is a part sectional end view of the inlet end of the drum of Fig. 6, the section being taken along the line 7—7;

Fig. 8 is a perspective view of the raw material feeder which communicates with the drum inlet;

Fig. 9 is a longitudinal vertical section through 35 the raw material feeder;

Fig. 10 is a transverse section through the feeder of Fig. 9, taken along the line 10—10;

Fig. 11 is a fragmentary section similar to 40 that of Fig. 9, showing the conveyor gate in action; and

Fig. 12 is an enlarged outside view of a fragment of the feeder showing a detail of construction thereof.

45 While our invention has been shown and described herein as being specifically applied to a rotary drier wherein material such as green hay is adapted to be drawn by suction along a circuitous path through the revolving drum, it is not the intent to thereby unnecessarily restrict the scope of utility of the improvement.

Referring to the drawings, the improved drier installation illustrated therein comprises in general a horizontally elongated externally insulated 50 rotary drying drum 15 having an inlet 16 at

one end and an outlet 17 at its opposite end, the drum being provided with end tires 18 cooperable with rollers 19 to rotatably support the same; a feeder 20 and a furnace 21 associated with the inlet end of the drum 15 and cooperating with the drier inlet 16 to constantly introduce a mixture of raw material and heated gas into the drying zone 22; a dry material discharge housing 23 and a gas separator 24 associated with the discharge end of the drum 15 and having therein a main fan 25 cooperating with the outlet 17 to constantly withdraw the mixture of treated material and spent heating medium from within the drum 15; and mechanism including a motor 90 enclosed within the housing 23, for rotating the fans, revolving the drum 15, and actuating the feeder 20.

The improved rotary drying drum in which the circuitous drying passage or zone 22 is confined, has therein an inner central cylindrical shell 27 communicating with the inlet 16 and provided with internal longitudinal hollow flights 28, and also has an intermediate shell 29 mounted therein between the shell 27 and the outer drum 15, see Figs. 6 and 7. The intermediate shell 29 and the drum 15 are also provided with internal longitudinal flights 30, 31 respectively; and the discharge end of the inner shell 27 is spaced from a partition 32 mounted within the shell 29 in spaced relation to the outlet 17, while the discharge end of the intermediate shell is spaced from the inlet end head of the drier drum, thereby providing the circuitous passage. The partition 32 is provided with a cone 33 on one side thereof for deflecting the stream of mixed solids and gases from the inner shell 27 into the intermediate shell 29, and has a cone 34 on its opposite side for deflecting the departing mixture through the outlet 17. The overhanging ends of the shells 27, 29 are mounted for free expansion longitudinally of the drum 15; and the hollow flights 28 within the shell 27 have their ends adjacent the cone 33 open while their opposite ends 35 are closed, but communicate through ports 36 with an annular chamber 37 which in turn is in open communication with the ambient atmosphere through ports 38. This construction of the flights 28 causes a constant circulation of relatively small quantities of cooling air therethrough during normal operation of the drier and protects these flights 28 against rapid deterioration due to exposure thereof to the hot gases entering the drying zone 22.

The improved special feeder 20 which is cooperable with the drier to insure uniform admission of an uninterrupted supply of raw material to the drying zone 22, is shown in detail in Figs. 8 to 12 inclusive, and comprises an elongated inclined casing 39 having a transverse partition 40 therein, the casing being provided at its lower end with an inlet hopper 41 and at its upper end with a downwardly directed delivery passage 42 communicating directly with the drier inlet 16; and an endless conveyor 43 having an upper stretch movable along the partition 40 and being provided with a series of material advancing flights 44. The endless conveyor 43 coacts with lower sprockets 45 mounted on a shaft which is journaled in adjustable lower bearings 46, and also coacts with upper sprockets 47 carried by an upper drive shaft 48 connected by chain gearing 49 to a counter shaft 50 having a clutch 51 associated therewith. The clutch 51 is operable to drivingly connect the counter shaft 50 with a sprocket 52 which is constantly driven by a 75

chain 53 coacting with another sprocket 54 rotatable by one of the drum carrying rollers 19, see Figs. 8 and 10.

The conveyor 43 is movable in the direction indicated by the arrow in Fig. 9, and a curved sealing plate 55 which is swingably suspended from a pivot shaft 56 coacts with the lower conveyor stretch and has a flat portion of sufficient length to span the gaps between three successive flights 44. The swinging lower end of the sealing plate 55 is adapted to be adjusted toward and away from the lower conveyor stretch by means of slotted elements 57 coacting with laterally projecting pins 58 on the plate, and nuts 59 coacting with threaded extensions 60 on the elements 57 and with flanges on the casing 39, as shown in Figs. 9 and 12. With this assemblage, the plate 55 is free to gravitate toward the lower inclined wall of the casing 39 and to thus urge the lower flights 44 against this wall, but if an obstruction causes the lower conveyor stretch to move upwardly, the pins 58 will ride upwardly within the slots in the elements 57 and will thus avoid damaging the conveyor 43.

A somewhat similar sealing plate 61 is also provided at the top run of the conveyor 43, the plate 61 being swingably suspended from a pivot shaft 62 and having side walls and a cover 63 associated therewith to form a movable box, see Figs. 9, 10, and 11. The plate 61 also has a flat portion which is adapted to span the gaps between three successive flights 44, and which is cooperable with the tops of the upwardly advancing flights of the upper conveyor stretch to normally provide a seal. The box assemblage is swingable by gravity toward the conveyor flights, but may be automatically elevated by excessive loads admitted to the conveyor 43 as in Fig. 11, and is also provided with a handle 64 for manual swinging. The top of the conveyor casing 39 may also be provided with an inspection slide or door 65 located between the hopper 41 and the seal plate 61, and another door 66 may be provided at the upper end of the casing 39 for inspection and air admission purposes.

The furnace 21 for supplying heated gases to the drying zone 22 through the inlet 16, may be either oil or gas fired, and is adapted to deliver the heating medium in swirling condition toward the inlet 16 and beneath the feeder delivery passage 42. The gravitating solids are thus spread and intimately mixed with the gaseous heating medium, and the temperature of this mixture may be modified by admitting regulated quantities of tempering air past the door 66. The furnace 21 may be readily detached from the drum 15 and feeder 20, and the feeder 20 may likewise be readily detached from the drum 15, so that the heating, feeding and drying units of the installation may be conveniently handled for shipment and installation.

The improved dry material discharge housing 23 which also serves to support the separator 24 and to enclose the power plant and auxiliaries, is shown in detail in Figs. 1 to 5 inclusive, and comprises three adjoining compartments 67, 68, 69 all forming part of the housing 23. The inner compartment 67 provides an enclosure for the main suction fan 25, and has a side inlet communicating directly with the drum outlet 17, and also has a tangential peripheral discharge passage 70 which is in open communication with the upper end of the cyclone separator 24. This separator 24 is of the well known type wherein the heavier particles are separated from the gases by centrif-

ugal force created by swirling the mixture about a central upper gas outlet, and in which the separated heavy solids or particles gravitate toward a lower outlet opening 71. The main fan 25 is mounted upon one end of a shaft 72 which passes entirely through the housing 23 axially of the drum 15, and the opposite end of this shaft has an auxiliary fan 73 mounted thereon and is also provided with a driving pulley 74, see Figs. 4 and 5.

The intermediate compartment 68 of the housing 23, has a downwardly directed fixed spout 75 therein which communicates directly with the separator outlet opening 71, and below this spout 75 is located an adjustable by-pass chute 76 and a heavy particle separator and final cooling conduit 77, see Figs. 2 and 3. The chute 76 is rectangular in transverse cross-section and is slightly longitudinally tapered, and is moreover swingably adjustably suspended by a hinge 78 so that the chute will normally tend to assume a position as indicated in Fig. 2, in vertical alinement with the spout 75. The chute 76 may be provided with a latch or other means for positively holding it in vertical position, although the suction normally existing therein will tend to maintain this chute in such position. The front of the chute 76 is provided with a normally closed sight opening 79, and may be swung about its suspension hinge 78 into the position shown in Fig. 3, whereupon material passing through the chute 76 may be discharged at the front of the compartment 68 directly from the separator 24. The medial portion of the inclined separator and cooling conduit 77 is upwardly open and is normally disposed in direct vertical alinement with the open lower end of the chute 76, and an adjustable baffle plate 80 attached to the front wall of the housing 23 extends toward the conduit axis and may be readily adjusted to various angular positions about a pivot 81 in order to vary the velocity of the flow. The lower end of the conduit 77 has an opening which may be closed by a cover 82, but the cover 82 may be disposed in open position as in Fig. 2 when the chute 76 is in vertical position. Above the medial upper opening in the inclined conduit 77, is a fixed downwardly extending baffle wall 83, and the upper end of this conduit 77 is curved laterally and extends into the outer compartment 69 axially of the shaft 72.

The outer compartment 69 of the housing 23 forms an enclosure for the auxiliary fan housing 84 within which the fan 73 is confined, and the axial inlet opening 85 of the fan 73 communicates directly with the separator conduit 77 while the peripheral tangential outlet 86 thereof communicates with a final delivery pipe 87 which may lead to any desired storage space or bagging zone. The housing compartment 69 may also be provided with front and rear inspection doors 88, 89, respectively, and besides enclosing the auxiliary fan, this compartment 69 also houses an electric motor 90 which is operatively connected to the fan driving pulley 74 by a belt 91. The motor 90 may also be drivingly connected in any suitable manner, with a universal driving connection 92 associated with one of the drum supporting rollers 19 through suitable reduction gearing located within an auxiliary housing 93, so that operation of the single motor 90 will produce simultaneous operation of the fans 25, 73, drum 15, and feeder 20. The rear door 89 is exposed to both compartments 68, 69, and is provided with a screen as shown in Fig. 2, for permitting passage of atmospheric air to the fan 73. The separator 24 may

be readily detached from the housing 23, and the housing 23 with its contents may be readily detached from the drum 15, for shipment, and the entire assemblage may therefore be conveniently handled in the form of segregated units for transportation, but may also be quickly assembled into a complete installation.

When the drier installation has been properly constructed and assembled, and the motor 90 is placed in operation, the fans 25, 73 are rotating, the drum 15 is revolving, and the feed conveyor 43 may be placed in operation by manipulation of the clutch 51. When the clutch 51 has been thrown into active position, the upper flights 44 of the endless conveyor will be advancing upwardly along the partition 40, and any material deposited within the hopper will naturally be carried upwardly toward the discharge openings 42 and deposited through this opening into the conduit leading from the furnace 21. During normal operation of the furnace 21, hot gases of combustion mixed with heated air are being delivered with a swirling motion through the drier inlet 16, and the bulk material which is being discharged in a constant stream through the outlet 42, will be mixed with the swirling hot gases, and the mixture will advance through the drier due to the suction created by the main fan 25 adjacent the drier outlet 17. During its passage through the drier drum 15, the solid particles of the mixture will be constantly showered across the interior of the shell 27 by the revolving flights 28, and the particles are ultimately drawn past the cone 33 into the intermediate shell 29 where the solid particles are further showered across the stream of hot gases. From the end of the shell 29, the mixture passes into the outer annular space where the revolving flights 31 further shower the solid particles and agitate the mixture, and the finally treated material is ultimately discharged through the outlet 17 along the cone 34. The fan 25 then propels the mixture of solids and gas through the main separator 24 wherein the spent gases of combustion and heated air are separated from the dry material, and the latter is discharged through the spout 75.

If the chute 76 is disposed as shown in Fig. 3, the dried material is by-passed to the exterior of the housing 23. If, however, the chute 76 is disposed as shown in Fig. 2, the dried material is drawn through the inclined conduit 77 and upwardly through the fan 73 where it is cooled and eventually delivered through the pipe 87. During passage of the solids into the conduit 77, the abnormally heavy particles such as stones and metallic particles, are separated by gravity and flow downwardly and out of the lower end of the conduit 77. The lighter dried product passes upwardly past the baffle 83 and through the fan 73, and is thoroughly cooled during this passage.

While the drier installation is operated in this manner, it is unnecessary to attempt to regulate the quantities of fresh material which are admitted to the hopper 41. The upwardly advancing flights 44 will withdraw quantities of material from the hopper 41, and if the quantities thus withdrawn project over the upper extremities of the upper flights 44, the shut-off plate 61 will be elevated slightly and will tend to spread the material over the conveyor. The plate 61 will function, however, to constantly maintain an air seal between the upper flights 44 and the lower face of the plate, thus preventing undesirable

entry of fresh air into the drying zone along the upper stretch of the conveyor 43. Simultaneously with this automatic functioning of the upper plate 61, the lower plate 55 will cooperate with the lower flights 44 of the conveyor to seal the passage of air along the lower stretch of the conveyor. In this manner excess quantities of fresh air are absolutely prevented from entering the drying zone, and if it is desired to admit small quantities of tempering air to this zone, then the door 66 may be adjusted.

From the foregoing detailed description it will be apparent that the present invention provides an improved drier installation which is extremely simple and compact in construction, and which is moreover highly efficient in operation. The formation of the inner flights 28 of the revolving drum, with air passages therethrough prolongs the life of the drier and also offers an opportunity for increased production. Due to the circulation of air through the flights 28, these flights do not become overheated and thus tend to eliminate scorching of material. The cooling of these flights also permits the use of higher inlet temperatures so that more material can be fed into the machine in order to absorb the additional heat.

The improved conveyor seal is relatively simple as compared to prior feeders for apparatus of this type, and has fewer moving parts which tend to wear rapidly. The sealing plates 61, 55 function automatically to produce a uniform stream of entering material, and to prevent undesirable ingress of cold air to the drying zone.

The improved housing 23 provides an enclosure for both fans, for the driving motor, and for accessory apparatus such as oil pumps, compressors, and expansion tanks. This housing also encloses the auxiliary separator and cooler, and serves as a support for the main separator 24. The housing 23 with the apparatus confined therein may be readily handled as a unit and thereby facilitates assembly of the installation. The adjustable chute 76 which permits direct by-passing of the treated product, is of considerable advantage in many instances, and the adjustable baffle 80 permits variation in the velocity of flow of the material through the conduit 71 so as to insure most efficient cooling and separation of abnormal particles.

The present improvement has proven highly advantageous in actual use, and it has been found that by providing detachable units such as earlier described, the installation can be readily assembled and dismantled in the shortest possible time. The drier drum 15 is preferably externally insulated so as to prevent undesirable loss of heat, and the furnace 21 should be likewise insulated. All mechanism of the installation is effectively protected against damage and from the weather, and the interior of the drying drum is also protected against deterioration due to overheating and is devoid of objectionable corners wherein material might accumulate.

With respect to subject matter illustrated and described but not claimed herein, reference is made to divisional application Serial No. 414,582 filed October 11, 1941.

It should be understood that it is not desired to limit this invention to the exact details of construction or to the precise mode of use, herein shown and described, for various modifications within the scope of the claims may occur to persons skilled in the art.

We claim:

1. In a drier, a drum forming a drying zone, means for maintaining sub-atmospheric pressure in said zone, a casing having a lower inlet and an upper outlet, the latter of which communicates with said zone, an endless conveyor within said casing having movable flights for delivering a constant stream of material from said lower inlet to said zone through said upper outlet,
- 5 10 15 20 25 30 35 40 45 50 55 60 65 70 75 80 85 90 95
2. In a drier, a rotary drum having a drying zone therein, means for introducing heated gas to said zone, an endless conveyor having a casing and having constantly advancing flights for delivering a continuous stream of bulk material to the gases entering said zone, and means for preventing uncontrolled admission of air with the material including an automatically adjustable swingable shutoff plate having a portion extending longitudinally of the conveyor between the ends thereof to simultaneously span a plurality of flights thereon and form a closure between said conveyor and the adjacent casing portions.
3. In a drier, a rotary drum having a drying zone therein, means for introducing heated gas to said zone, an endless conveyor having a casing and having constantly advancing flights for delivering a continuous stream of bulk material to the gases entering said zone, and means for preventing uncontrolled admission of air with the material including an automatically adjustable swingable shutoff plate having a portion extending longitudinally of the conveyor between the ends thereof and normally urged by gravity into contact with said conveyor to rest on a plurality of flights simultaneously and form a closure between said conveyor and adjacent casing portions.
4. In a drier, a drying drum having a drying zone therein, a conveyor casing having an inlet and an outlet, the latter of which communicates with said zone, an endless conveyor within said casing having movable flights for delivering a constant stream of material from said inlet through said outlet into said zone, said casing having an upper wall formed with an opening, and an air seal pivotally supported from said upper wall of the casing adjacent said opening and normally closing the latter, said air seal being swingable in a direction both inwardly and outwardly of the casing and normally coacting with said moving flights to form a closure between said flights and adjacent casing portions and thereby prevent admission of uncontrolled quantities of fresh air to the drying zone along the delivery stretch of the conveyor, and means for preventing admission of uncontrolled quantities of air between the bottom of the delivery stretch of the conveyor and the bottom wall of the casing.
5. In a drier, a drying drum having a drying zone therein, a conveyor casing having an inlet and an outlet, the latter of which communicates with said zone, an endless conveyor within said casing having movable flights for delivering a constant stream of material from said inlet

through said outlet into said zone, imperforate means positioned within the casing and extending between the delivery and return stretches of the conveyor normally urged against the return stretch of the conveyor to press the flights of the latter against the lower wall of the conveyor casing, and means for preventing admission of uncontrolled quantities of air above the delivery stretch of the conveyor.

6. In a drier, a drying drum having a drying zone therein, a conveyor casing having an inlet and an outlet the latter of which communicates with said zone, an endless conveyor within said casing having movable flights for delivering a constant stream of material from said inlet through said outlet into said zone, an air seal member pivotally supported for swinging movement within the casing and extending between the delivery and return stretches of the conveyor, said air seal member being urged by gravity against the inner side of the return stretch of the conveyor to press the flights of the latter against the lower wall of the conveyor casing, and means for preventing admission of uncontrolled quantities of air above the delivery stretch of the conveyor.

7. In a drier, a drying drum having a drying zone therein, a conveyor casing having an inlet and an outlet, the latter of which communicates with said zone, an endless conveyor within said casing having movable flights for delivering a constant stream of material from said inlet through said outlet into said zone, an air seal member pivotally supported for swinging movement within the casing and extending between the delivery and return stretches of the conveyor, means including a pin and slot connection for guiding the free end of said air seal member in swinging movement and for limiting the extent of movement thereof, said air seal member being normally urged by gravity against the inner side of the return stretch of the conveyor to press the flights thereof against the lower wall of the conveyor casing, and means for preventing ad-

mission of uncontrolled quantities of air above the delivery stretch of the conveyor.

8. In a drier, a drying drum having a drying zone therein, a conveyor casing having an inlet and an outlet, the latter of which communicates with said zone, an endless conveyor within said casing having movable flights for delivering a constant stream of material from said inlet through said outlet into said zone, an air seal member pivotally supported for swinging movement within the casing and extending between the delivery and return stretches of the conveyor, guide members having slots therein which extend transversely of the direction of movement of the conveyor, means for adjusting the position of said guide members to vary the position of the lower ends of the slots with respect to the lower stretch of the conveyor, pins on the free end of said air seal member cooperable with said slots, said air seal member being movably engaged with the inner side of the return stretch of the conveyor to press the flights thereof against the lower wall of the conveyor casing, and means for preventing admission of uncontrolled quantities of air above the delivery stretch of the conveyor.

9. In a drier, a drying drum having a drying zone therein, a conveyor casing having an inlet and an outlet, the latter of which communicates with said zone, an endless conveyor within said casing having movable flights for delivering a constant stream of material from said inlet through said outlet into said zone, imperforate means co-acting with the delivery stretch of the conveyor and extending to the top wall of the casing to prevent uncontrolled admission of cold air with the material, and imperforate means positioned in the casing and extending between the delivery and return stretches of the conveyor normally engaging the inner side of the return stretch of the conveyor to press the conveyor flights against the lower wall of the conveyor casing.
